UNITED STATES PATENT OFFICE.

JOHN JUNGERS, OF GRAFTON, WISCONSIN.

COUNTERBALANCED OVEN-DOOR.

1,187,743.

Specification of Letters Patent. Patented June 20, 1916.

Application filed October 20, 1913. Serial No. 796,123.

To all whom it may concern:

Be it known that I, JOHN JUNGERS, a citizen of the United States, and resident of Grafton, in the county of Ozaukee and State 5 of Wisconsin, have invented new and useful Improvements in Counterbalanced Oven-Doors, of which the following is a description, reference being had to the accompanying drawings, which are a part of this specification.

This invention has for its object to provide a downwardly swinging oven door for ranges or the like which will be counterbalanced in all positions thereof so as to 10 make the opening and closing of the door easily accomplished and so as to avoid the slamming of the door and its injurious effects upon the contents of the oven when baking is in progress.

Another object of the invention is to provide a counterbalance for oven doors to 15 occupy the space between the oven and the fire box.

With the above and other objects in view 20 the invention consists in the counterbalanced oven door as herein claimed and all equivalents.

Referring to the accompanying drawings in which like characters of reference indicate 25 the same parts in different views; Figure 1 is a sectional elevation of a range equipped with the counterbalanced oven door in accordance with this invention, the oven door being shown in full lines in its closed 30 position and in dotted lines in its open position; Fig. 2 is a similar view showing the oven door in an intermediate position, a portion of the weight shifting link being broken away to show its bearing surface for 35 the weight arm; Fig. 3 is a sectional plan view of the parts on the plane of line 3-3 of Fig. 2; and, Fig. 4 is a sectional rear elevation on the plane 4-4 of Fig. 1.

In these drawings 10 indicates a range 40 of ordinary construction and 11 is the oven door thereof which has trunnions 12 at its lower edge on which it is pivotally mounted to swing downwardly to its open position as shown in Fig. 2 and by dotted lines in Fig.

50 1. One of the trunnions 12 is squared at its end to fit in a correspondingly shaped opening of an arm 13 which projects through an opening in the front of the range into the space 14 between the oven 15 and the fire 55 box 16. Any other desirable form of connection may be provided for the arm 13 to

make it rigid with the oven door and a cap or covering 17 is desirably secured to the front of the range to inclose this connection and form the bearing for the trunnion 12. 60 In the closed or upper position of the oven door 11 the arm 13 extends downwardly as shown in Fig. 1. At its inner end the arm 13 may be made forked, as seen in Fig. 3, and it is pivotally connected to a weight 65 shifting link 18 which carries a head 19 having an oblique slotted projection 20 through which a pivot bolt 21 passes, such pivot bolt being carried by an arm 22 which is pivotally mounted at 23 in the upper front corner 70 of the space 14 and carries a weight 24 at its lower end. Besides the oblique slotted projection 20 the head 19 has a curved bearing surface 25 to come into engagement with the lower edge of the weight arm 22 when 75 the oven door is in an intermediate position and remains in engagement therewith throughout the lower portion of the travel of the oven door. This bearing surface 25 stands at such an angle with relation to the 80 other portion of the link 18 that the point of contact between it and the weight arm 22 is constantly shifted during the lower portion of the movements of the oven door, such point of contact moving nearer to the 85 pivotal connection 23 of the weight arm as the oven door approaches its lowermost position and receding from the pivotal connection 23 as the oven door rises from its lower position thus varying the 90 leverage and causing the weight to become more effective in counterbalancing the oven door. The weight naturally becomes more effective for counterbalancing the oven door as the weight arm approaches the horizontal 95 but this shifting of the link bearing on the weight arm due to the bearing surface 25 rocking on the weight arm so as to bring the point of contact nearer to the pivotal connection of the weight arm increases such 100 tendency. This tendency is further increased by reason of the curvature of the bearing surface 25 being such that its point of contact with the weight arm is progressively farther from the pivotal connection 105 between the link 18 and the arm 13 as the oven door approaches its open position, thus having the effect of increasing the length of the link connection. The varying leverage is further affected by the slotted oblique projection 20, for the pivot bolt 21 slides 110 through the slot thereof during the move-

ment of the oven door while the weight arm 22 is resting on the bearing surface 25 and the direction of the slot is such as to force the bearing surface 25 to slide on the weight arm as well as rock thereon, thus further reducing the distance from the pivotal connection 23 to the point of bearing of the weight arm on the bearing surface 25 of the link as the oven door approaches an open position. To strengthen the curved bearing surface 25 and to guide the parts said bearing surface is provided with a side cheek 26 which is broken away in Fig. 2 but which is shown in Fig. 1.

15 By means of this invention the oven door in swinging from its vertical position to its horizontal position is opposed by an increasing resistance due to the weight arm increasing its effectiveness by moving toward a horizontal position and also due to the variation in the leverage caused by the shifting of the bearing point between the link and the weight arm approaching the pivotal connection of the weight arm and also the increasing effective length of the link 18, the change in bearing point being produced by the rocking of the link on the weight arm as well as by the cam action of the inclined slot on the pivot bolt 21 causing the bearing surface of the link to slide on the weight arm.

It is found in practice that in this manner the oven door may be so perfectly counterbalanced that it may stand at rest 35 in any inclined position thereof so that it is very easily moved but will not slam either in opening or closing. By locating the counterbalancing system within the space between the fire box and the oven it is concealed without interfering with the normal 40 operation of the range and without the necessity for increasing the size of the range.

What I claim as new and desire to secure by Letters Patent is:

45 1. In an oven door or the like swinging on a horizontal axis, a counterbalancing means therefor, comprising an arm having connection with the door, a swinging weight arm, and a link connected with the first mentioned arm and having a curved bearing surface engaging the weight arm with the point of engagement therewith approaching the pivotal connection of the weight arm as the door approaches its horizontal position, said bearing surface being eccentric with relation to the pivotal connection between the link and the door arm with the portion of the bearing surface nearest the pivotal connection in engagement with the weight arm 50 in the closed position of the oven door to increase the effective length of the link as the door approaches its horizontal position.

2. In an oven door or the like swinging on a horizontal axis, a counterbalancing means therefor, comprising an arm having connection with the door, a swinging weight arm, a link pivotally connected with the first mentioned arm and having a bearing surface for engaging the weight arm, a slotted projection on the link, and means on the weight arm engaging the slotted projection for causing the bearing surface of the link to slide on the weight arm toward the pivotal connection of the weight arm as the door approaches its horizontal position. 75

3. In an oven door or the like swinging on a horizontal axis, a counterbalancing means therefor, comprising an arm having connection with the door, a swinging weight arm, a link pivotally connected with the first mentioned arm and having a curved bearing surface eccentric to the pivotal connection between the link and the bearing arm, a slotted projection on the link, a bolt on the weight arm passing through the slotted projection for pivotally connecting the link with the weight arm and causing the weight arm to swing when the door begins its movement from a vertical position toward a horizontal position, said bearing surface adapted to engage the weight arm and cause the bolt to slide through the slot of the link to force the bearing surface to slide on the weight arm toward the pivotal connection of the weight arm. 80

4. In an oven door or the like swinging on a horizontal axis, a counterbalancing means therefor, comprising an arm having connection with the door, a swinging weight arm, a link pivotally connected with the first mentioned arm and having a bearing surface for engaging the weight arm, and means for causing the bearing surface of the link to slide on the weight arm toward the pivotal connection of the weight arm as the door approaches its horizontal position. 95

5. In an oven door or the like swinging on a horizontal axis, a counterbalancing means therefor, comprising an arm having connection with the door, a swinging weight arm, a link pivotally connected with the first mentioned arm and having a curved bearing surface for rocking engagement with the weight arm, and means for causing the bearing surface of the link to rock and slide on the weight arm toward the pivotal connection of the weight arm as the door approaches its horizontal position. 100

In testimony whereof, I affix my signature, in presence of two witnesses.

JOHN JUNGERS.
